CREEL

Filed Jan. 11, 1929

Inventor:
Fay H. Martin
by Chas. F. Randall
Atty.

UNITED STATES PATENT OFFICE

FAY H. MARTIN, OF WOONSOCKET, RHODE ISLAND, ASSIGNOR TO WHITIN MACHINE WORKS, OF WHITINSVILLE, MASSACHUSETTS, A CORPORATION OF MASSACHUSETTS

CREEL

Application filed January 11, 1929. Serial No. 331,852.

The invention has relation to creels on the order of those which are employed in various manufacturing processes for supporting bobbins, spools, or the like, loaded with supplies of rovings, yarns and the like, which are to be operated upon, in convenient relations for the paying-out of the material that has been wound thereon.

More particularly, the invention has relation to creels of the class in which the supply-bobbins, spools, or the like, are supported in place, conveniently for the delivery of their contents, by skewers or spindles mounted in upright positions with their lower ends or feet resting upon suitable steps and with their upper ends or tips confined by tip-retainers.

The invention provides in novel manner for mounting and supporting skewer-supporting steps in their proper working relations in connection with tubular and other shell-like creel-rails of curvilinear or analogous cross-section.

The nature and features of the invention are illustrated by the accompanying drawings, in which,—

Fig. 1 shows in vertical section two rails of a roving creel with the invention applied thereto, and in elevation a bobbin carrying a load of roving.

Fig. 2 is a front elevation of a portion of one of the rails of Fig. 1.

Fig. 3 is a top or plan view of the said portion.

Figs. 4, 5, 6, are respectively a front elevation, a side elevation, and a top plan view, of one of the steps of Figs. 1, 2, 3.

Fig. 7 is a top view of one of the tip-retainers to which references are made later herein.

The invention is capable of application to creels in general having rails such as aforesaid. It will be described with reference, more particularly, to application in connection with a roving-bobbin creel, such, for instances, as one for a roving-frame, a spinning-frame, or a spinning mule, as the case may be.

Inasmuch as the creel of one of the named machines is somewhat long, and contains in

its general make-up constructional features that are not involved in the invention, and inasmuch as the invention has reference to only the steps by means of which bobbin-supporting skewers are mounted in connection with the longitudinally-extending bobbin-supporting elements of a creel, and to the manner and means of supporting the steps in position in connection with the said longitudinally-extending elements, the drawings have been restricted to short portions of the lengths of two rails 1, 1, and to steps and step-supporting means constituted by skewer-tip retaining devices applied to such portions. This extent of illustration will suffice for making clear the following disclosure of the features and principles of the invention. The said two rails are supposed to be ones which are employed at intermediate heights in a creel. In the drawings, each rail 1, 1, is shown equipped with a skewer-supporting step 2, and with a skewer-tip-retainer 3. In practice, the rails extend in the direction of the length of the creel of which they constitute elements, and each thereof is equipped with a plurality of steps and with an associated plurality of tip-retainers. In Fig. 1 a bobbin 4, having a load or roving 5 wound thereon, is shown mounted upon a skewer 6 that is supported by having its foot or pintle stepped in the concavity of the top of a step 2 in connection with the lower rail, the skewer and bobbin being maintained in upright position by means of tip-retainer 3 in connection with the upper rail, such tip-retainer being nearly in vertical alinement with the said step, and the opening of the eye of such retainer being occupied by the skewer-tip.

The skewer-tip-retainer shown in Fig. 1 in connection with the lower rail is intended to serve in practice to confine the tip of a bobbin-skewer (not shown) that is stepped below such rail; the step shown in connection with the upper rail is intended to receive the foot or pintle of a bobbin-skewer that is restrained at its tip by a tip-retainer carried by a higher rail (or other support) not shown. The number of rows or banks, one above another, of supply-bobbins provided for in

the construction of a creel varies in practice, and accordingly the number of rails, one above another, in a creel embodying the invention, varies in practice. Every rail of a 5 creel except the top one is equipped with steps, and every one except the bottom rail is equipped with tip-retainers disposed above steps located below such rail, so that each tip-retainer may encircle the tip of a bobbin- 10 carrying skewer stepped in a step below such tip-retainer while keeping such skewer and the associated bobbin upright.

The rails 1, 1, are constituted of tubing, as described and claimed in my application 15 for U. S. Letters Patent for improvement in creels, filed January 8, 1929, Serial No. 331,044.

The skewer-supporting steps are mounted in the upper portions of the said rails, and 20 the tip-retainers are applied so that the skewer-tip-receiving eyes thereof project horizontally from the vertically curved surface at one side of each rail.

Tubular and other shell-like creel-rails of 25 curvilinear or analogous construction have a number of advantages to which references are made in my application aforesaid. It is a leading object of the present invention to provide in simple, practical, and efficient 30 manner for combining skewer-supporting steps with rails of such type.

The steps 2, 2, may be composed of any material suitable for the purposes involved. In general practice heretofore, similar steps 35 have been composed of porcelain, and such material may be employed in carrying the present invention into practical effect. The form of a step 2, may be varied more or less in practice. In the illustrated instance it is 40 cylindrical in horizontal cross-section, with a concavity in its top to constitute a bearing receiving the foot or pintle of a skewer 6. In the top side of a rail 1 a hole is made for occupancy by the step, there being in practice 45 a longitudinal series of like holes corresponding in number with the number of skewers and bobbins comprised in a row or bank thereof to be provided for. The said hole corresponds in shape with the cross-sectional 50 shape of the step, which latter fits snugly within the hole and is supported therein, preferably with its top substantially flush with the top surface of the rail.

For the vertical support of the respective 55 steps 2, 2, in connection with the rails, I provide for each step a wire, 31, Figs. 1, 2, 7, extending across the shell of a rail 1 from front to rear of the latter, as in Figs. 1 and 3, below the working position of the step. 60 This wire limits the descent of the step within the hollow of the rail. The step thus supported within the rail is enclosed and protected by the latter. Inasmuch as the upper end or top of the step preferably is almost 65 flush with the top surface of the rail, there

exists little in the nature of a projection to accumulate or detain lint and the like. In virtue of the step being contained mainly within the rail 1, and enclosed by the latter, it is shielded against blows and resulting 10 injury, and against dislodgment by blows or through being acted upon in cleaning operations.

Preferably a notch 21, Figs. 2 and 4, is formed in the foot portion of the step, at the 15 bottom thereof, to receive the wire 31. Through the engagement of the walls of the said notch with the said wire, side-motion of the foot portion of the step is prevented. Thereby the step is prevented from becoming 20 canted sidewise and thereby cramped within the hole occupied by it in the shell or wall of the rail, and also from slipping laterally from the wire and dropping out of place. To facilitate introduction of a step 25 into the hole therefor in rail 1, the foot portion of the step may be tapered or beveled as shown.

Preferably, the wire 31 is constituted by the 30 stem of a skewer-tip-retainer 3. The construction and form of the retainer may vary somewhat in practice, although the particular tip-retainer shown in the drawings is preferred.

This tip-retainer 3 comprises a wire of U 35 or staple-form, which is combined with a rail 1 with the bend of the U projecting outward from the surface of the said rail. The bend stands out from the said surface, and the two legs of the U are spaced apart at the surface 40 of the rail sufficiently to provide an eye proportioned properly to contain a skewer-tip as in Fig. 1, as well as to permit sufficient play and free turning of the tip within such eye. One of the legs is long and constitutes the 45 stem 31 of the top-retainer, the other leg being short. The long leg or stem 31 extends horizontally, diametrically across the tubular rail, such leg occupying holes in the shell or wall of the rail at opposite sides of the 50 latter and being made fast in place by riveting at its extremity. The portion of such extremity which occupies the corresponding hole in the said shell or wall is reduced in diameter to produce a shoulder 32 which, 55 through engagement with the inner surface of such shell or wall prevents displacement of the tip-retainer in one direction, while the burr on the exposed outer portion of the long leg prevents displacement in the opposite direction. The short leg of the tip-retainer occupies a hole in the shell or wall at the side 60 of the latter at which the eye is located, but in this instance extends only a short distance within the tubular rail. The engagement of the two legs of the tip-retainer within holes in the shell or wall of the tubular rail at 65 points separated from each other prevents the tip-retainer from turning so as to displace the eye angularly into a position ren- 70 110 115 120 125 130

dering it difficult of entry by a skewer-tip. As an obvious modification, the tip-retainer may be formed with two long legs, both extending across the tubular rail and made fast as described above with reference to the long leg aforesaid, and both legs serving to support the step. By reason of the said legs being spaced apart horizontally from each other between the points where they intersect the surface of the rail, no obstruction is presented in the case of a skewer-tip laid against the convex surface of the lower portion of the rail, that is to say below the eye, and pushed upward over such surface endwise into the eye. This operation admits of being performed quickly. The surface of the rail guides the skewer-tip into the inner portion of the eye, so that, provided the said tip has been alined with the opening of the eye, and that lateral deviation from alinement is avoided, the introduction of the tip into the eye takes place readily. The operation of mounting an associated bobbin and skewer in place in a creel is capable of being performed by one hand holding the associated bobbin and skewer, without the assistance of the other hand, by operations involving placing the tip against the surface of the rail below a tip-retainer, sliding the tip upward upon said surface into the opening of the eye of the tip-retainer, and dropping the foot of the skewer into the properly-related step provided below.

The principles and advantages of the invention may be utilized through application to creel-rails of other shell-like forms.

The tip-retainer per se is claimed in my companion application filed January 8, 1929, Serial No. 331,044.

40 What is claimed as the invention is:—

1. In a creel, the combination with a shell-like creel-rail having a step-receiving hole in the upper portion thereof, of a skewer-foot supporting step, and a step-engaging member extending across the concavity of the rail below the said hole to support the step.

2. In a creel, the combination with a shell-like creel-rail having a step-receiving hole in the upper portion thereof, of a skewer-foot supporting-step having a transversely-extending notch in its base, and a step-supporting wire extending across the interior of the rail below the said hole and occupying the said notch.

3. In a creel, the combination with a shell-like creel-rail having a step-receiving hole in the upper portion thereof, of a skewer-foot supporting-step and a skewer-tip retainer having a tip-receiving eye located exteriorly of the creel-rail and a stem extending across the interior of the rail below the said hole to afford vertical support to the step.

4. In a creel, the combination with a shell-like creel-rail having a step-receiving hole in the upper portion thereof, of a skewer-foot

supporting-step, and a skewer-tip retainer of U-shape combined with said rail with the bend of the U projecting outward from the rail-surface and the two legs of the U spaced apart to constitute a skewer-tip receiving eye, and with at least one leg extending across the interior of the rail below the said hole to limit the descent of the step within the rail.
